BRAKING MECHANISM FOR RAILWAY CAR TRUCKS

Harry A. Moeller and Claude L. Orr, Columbus,
Ohio, assignors to The Buckeye Steel Castings
Company, Columbus, Ohio

Application May 6, 1937, Serial No. 141,156

16 Claims. (Cl. 188—33)

This invention relates to improvements in brake operating mechanism for railway car trucks, and more particularly to improvements in mechanism of the type actuated by one or more pistons.

Heretofore the air cylinder or cylinders for the piston or pistons were mounted on the body of the car. Recently, however, due to higher train speeds and extremely heavy equipment, the older method of transmitting through pull rods the forces for the application of brakes to the wheels of a truck from an air cylinder mounted on the body of the vehicle, has been improved by providing air cylinders mounted on the truck. Such improvement is exemplified in the application of Stertzbach and Moeller Serial No. 100,169, filed September 10, 1936. The means disclosed in that application reduces weight by eliminating long pull rods and heavy body lever arrangements, and consequently, such means may be maintained at less expense and has greater economy and efficiency than the former means of mounting brake cylinders.

In accordance with the present invention, the cylinder is so mounted as to be spring supported, and this is accomplished by mounting the cylinder directly on a spring-supported, transverse bolster of the truck or partially on the bolster and partially on a side frame of the truck. Due to this arrangement the cylinder is positioned outside of the side frame system where it may be readily reached for any purpose.

For a clear understanding of our invention and to illustrate certain forms of the same, reference is had to the accompanying drawings, in which

Fig. 1 is a side elevation of one end portion of a railway car truck showing an embodiment of our invention in which the carrier for the air cylinder is supported partially by the side frame and partially by the transverse bolster.

Fig. 2 is a top plan view.

Fig. 3 is a sectional view of a detail taken on the line 3—3 of Fig. 1.

Fig. 4 is a view similar to Fig. 1 but showing a modification in which the carrier is mounted directly on the transverse bolster.

Fig. 5 is a top plan view of the same.

Fig. 6 is a side elevation of another modification in which the carrier is mounted directly on the transverse bolster.

Fig. 7 is an end view of the structure shown in Fig. 5.

The improvements disclosed herein may be employed with braking mechanism of the type shown in said Stertzbach and Moeller applica-

tion. The latter involves mounting one brake cylinder between the side frame systems and on the center bolster system. In our present construction, instead of one brake cylinder on each truck, we show the cylinder mounting on the outside of the side frame system. With the brake cylinder mounted outside of the side frame, at least two cylinders are required for each truck and preferably both cylinders mounted on one end of the truck. The end on which the cylinders are mounted is designated as the "live" end and the other, as the "dead" end. If both ends are each equipped with two cylinders, then both ends would be designated as "live" ends.

Referring to Figs. 1 to 3 inclusive, 8 designates a portion of a side frame of a six-wheel truck having a conventional opening 9 to receive one of the transverse bolsters 10 which is shown in dotted lines in Fig. 2. 11 indicates one of the wheels on which the side frame is mounted.

In accordance with the present invention a carrier 12 has one of its ends pivotally connected by a slot and pin joint 13, to a bracket 14 which may be integral with or secured to the side frame. The opposite end of the carrier is pivotally connected at 15 to a bracket 16 that is designed to be mounted on the transverse bolster 10. As the bolster is supported by springs, it is obvious that one end of the carrier can move upwardly and downwardly with the bolster.

An air cylinder 17 is supported by the carrier, and its piston rod is pivotally connected at 18 to a lever 19 which fulcrums at 20 on one end of a link 21 that is pivotally secured at 22 to the carrier. A rod 23 has one of its ends pivotally connected at 24 to the medial portion of the lever and its opposite end pivotally connected at 25 to a portion 26 of the brake mechanism.

The weight of the lever 19, link 21 and rod 23 must be supported by some means other than the piston rod 27. This support is provided by a split carrier block arrangement 28 (see Fig. 3) consisting of an upper section 28a and lower section 28b; the former being retained by the bolt 15 and the latter by a pocket 28c in the bracket 16. The rod passes through recesses 28d in such sections, and rests on the section 28b. The carrier block is split for the purpose of assembling the various parts.

The arrangement shown operates the brake on one side of the truck. The brake on the other side of the truck is operated by a similar arrangement opposite and on the same end of the truck. It will be obvious that when the piston rod moves outwardly, the lever 19 will fulcrum at 20 and 55

pull the rod 23 for the purpose of applying the brakes.

In the modification shown in Figs. 4 and 5, the carrier 30 is mounted directly on one end of the bolster 31 and is secured in position by any suitable means such as bolts 32.

The air cylinder 33 is mounted on the carrier, and the piston rod 34 is pivotally connected at 35 to a lever 36 that is fulcrumed at 37 on the outer end of a link 38. The latter is pivotally connected at 39 to the carrier. The brake operating rod 40 slides between rollers 41 mounted in the carrier, and of course, the rod is pivotally connected at one end to the lever and is pivotally connected at its opposite end to a part of the brake mechanism 42.

In Figs. 6 and 7, the link is replaced by an arm 50 which is integral with the carrier 51; the latter being directly mounted on one end of the transverse bolster 52. The cylinder 53 in this instance, is also mounted on the carrier, and the piston rod 54 actuates the lever 55 which effects movement of the brake operating rod 56. Since in this arrangement the lever 55 is supported by an arm which is rigidly united with the carrier, it is not necessary to further guide or support the pull rod 56.

The three arrangements described above have the brake cylinder mounted wholly or partially on the end of the transverse bolster in order to realize the advantage of having the cylinder spring-supported.

The drawings show the improved mechanism applied to a six-wheel truck, but it is manifest that such mechanism is applicable to trucks of any number of wheels.

While we have disclosed what we now consider to be preferred embodiments of the invention, it is apparent that changes may be made in the details disclosed without departing from the spirit of the invention as expressed in the claims.

What we claim and desire to secure by Letters Patent is:

1. A railway car truck including a side frame member and a transverse bolster, an air cylinder mounted on an end of said bolster and having a piston rod, and brake actuating mechanism operatively connected to the piston rod.

2. A railway car truck including a side frame member and a transverse bolster, an air cylinder supported at least partially by said bolster and having a piston rod, and brake actuating mechanism operatively connected to the piston rod, said cylinder being arranged outwardly of the side frame member.

3. A railway car truck comprising a side frame member and a transverse bolster, a carrier supported in part at least by said bolster, an air cylinder supported by the carrier and having a piston rod, and brake operating mechanism operatively connected to the piston rod.

4. A railway car truck comprising a side frame member and a transverse bolster, a carrier supported in part at least by the bolster, an air cylinder mounted on the carrier and having a piston rod, a lever having one of its ends pivotally connected to the piston rod, means pivotally connecting the opposite end of the lever to said carrier, and a brake-operating rod pivotally connected to the medial portion of the lever.

5. A railway car truck comprising a side frame member and a transverse bolster, a carrier supported in part at least by the bolster, an air cylinder mounted on the carrier and having a piston rod, a lever having one of its ends pivotally

connected to the piston rod, means pivotally connecting the opposite end of the lever to said carrier, a brake-operating rod pivotally connected to the medial portion of the lever, and means forming a support for said rod.

6. A railway car truck comprising a side frame member and a transverse bolster, a carrier arranged at one side of the side frame member and supported at least partially by said bolster, an air cylinder mounted on the carrier and having a piston rod, a lever actuated by said rod, and a brake-operating member operatively connected to and actuated by the lever.

7. In a railway car truck, a side frame member, a transverse bolster, an air cylinder supported in part at least by said bolster and having a piston rod, a lever operatively connected to said rod, and a brake actuating rod slidably supported by the bolster and operatively connected to said lever.

8. The combination with a railway truck side frame member and transverse bolster, of a carrier operatively connected to said member and bolster and supported in part by the latter, an air cylinder mounted on the carrier and having a piston rod, and brake-operating mechanism operatively connected to said piston rod.

9. The combination with a railway car truck side frame member and transverse bolster, of a carrier having one of its ends pivotally connected to the side frame member and its other end pivotally connected to the bolster, an air cylinder supported by the carrier and having a piston rod, and brake-actuating mechanism operatively connected to said piston rod.

10. The combination with a railway car truck side frame member and transverse bolster, of a carrier having one of its ends pivotally connected to the side frame member and its other end pivotally connected to the bolster, an air cylinder supported by the carrier and having a piston rod, brake-actuating mechanism operatively connected to said piston rod, said brake-actuating mechanism comprising a pivotally mounted lever having one of its ends connected to the piston rod, and a brake actuating rod pivotally connected to said lever.

11. In combination with a railway truck side frame member and transverse bolster, of a carrier having one of its ends pivotally supported by the side frame member and its other end pivotally supported by the bolster, an air cylinder mounted on the carrier and having a piston rod, a lever having one of its ends pivotally connected to the piston rod, means pivotally connecting the other end of the lever to the carrier, and a brake-operating rod pivotally connected to the medial portion of the lever.

12. The combination with a railway truck side frame and transverse bolster, of an air cylinder mounted on one end of the bolster and having a piston rod, a lever having one of its ends pivotally connected to the piston rod, means operatively connecting the other end of the lever to the bolster, and a rod slidably mounted between the cylinder and bolster and having one of its ends pivotally connected to the medial portion of the lever.

13. The combination with a railway truck side frame member and transverse bolster, of a carrier mounted on one end of the bolster, an air cylinder supported by the carrier and having a piston rod, a lever pivotally connected to the piston rod, means operatively and pivotally connecting the lever to the bolster, a support carried

by the carrier, and a brake-operating rod guided by said support and having one of its ends pivotally connected to said lever.

14. In combination with a railway truck side frame member and a transverse bolster, of a carrier supported by the bolster and having a projecting arm, an air cylinder mounted on said carrier and having a piston rod, a lever pivotally supported by said arm and pivotally connected to the piston rod, and a brake-operating rod operatively connected to said lever.

15. The combination with a railway truck side frame member and a transverse bolster, of an air cylinder supported in part at least by one end of the bolster and arranged outwardly of the side frame member, a lever having one of its ends pivotally and operatively connected to said bol-

ster, a piston rod projecting from the cylinder and operatively connected to the other end of the lever, and a brake-actuating rod operatively connected to the medial portion of the lever.

16. The combination with a railway truck side frame member and transverse bolster, of a carrier mounted on one end of the bolster, an air cylinder supported by the carrier and having a piston rod, a lever pivotally connected to the piston rod, means operatively and pivotally connecting the lever to the bolster, a roller support carried by the carrier, and a brake-operating rod guided by said roller support and having one of its ends pivotally connected to said lever.
